UNITED STATES PATENT OFFICE

140,509

DESIGN FOR A COMBINED REMOTE CONTROL AND POSITION INDICATOR FOR AIRPLANE PARTS

William P. Lear, North Hollywood, Calif., assignor to Lear, Inc., Piqua, Ohio, a corporation of Illinois

Application October 5, 1944, Serial No. 115,622

Term of patent 14 years

(Cl. D71—1)

To all whom it may concern:

Be it known that I, William P. Lear, a citizen of the United States of America, residing at North Hollywood, in the county of Los Angeles, in the State of California, have invented a new, original, and ornamental Design for a Combined Remote Control and Position Indicator for Airplane Parts, of which the following is a specification, reference being had to the accompanying drawings, forming a part thereof.

In the drawings:

Fig. 1 is a top plan view of a combined remote control and position indicator for airplane parts illustrating my new design.

Fig. 2 is a front elevational view of the position selector and indicator shown in Fig. 1.

Fig. 3 is a bottom plan view of the position selector and indicator shown in Fig. 1.

Fig. 4 is a rear elevational view of the position selector and indicator shown in Fig. 1.

Fig. 5 is a left end elevational view of the position selector and indicator shown in Fig. 1.

I claim:

The ornamental design for a combined remote control and position indicator for airplane parts, substantially as shown.

WILLIAM P. LEAR.
